UNITED STATES PATENT OFFICE.

HUBERT J. LA JOIE, OF EAST ORANGE, NEW JERSEY, AND UBERT URQUHART AND FRANK POKORNY, OF NEW YORK, N. Y., ASSIGNORS TO AUTO PNEUMATIC ACTION COMPANY, OF NEW YORK, N. Y., A CORPORATION OF NEW YORK.

EXPRESSION-CONTROLLING MECHANISM FOR PNEUMATICALLY-OPERATED MUSICAL INSTRUMENTS.

Application filed September 22, 1922. Serial No. 589,871.

The object of our present invention is particularly to improve and add to the expression controlling mechanism shown, described and claimed in an application for Letters 5 Patent of the United States, filed by us October 31, 1921, Serial No. 511,711, forming Letters Patent #1,603,342, dated October 19, 1926. In said application for patent a mechanism consisting of the development of 10 the invention shown in patent to Welte, No. 1,225,902 dated May 15, 1917, is illustrated and which mechanism comprises a valve unit applied to co-operate with one part of a divided action for an automatic musical instrument and another valve unit applied to 15 co-operate with the other section thereof. Each unit has an automatic governor which can be set to work to utilize different degrees of tension by an expression pneumatic 20 controlled automatically from the tracker bar. This adjustment is obtained by arranging an expression valve to co-operate with the governing valve, which expression valve is moved to different positions for different degrees of playing and is moved slowly 25 away from the governing valve for a crescendo effect and slowly towards the governing valve for a diminuendo effect. It has been found desirable to adjust the rate of 30 movement of the expression pneumatics so that the length of time of the diminuendo or crescendo effects can be adjusted. It is not very easy to adjust the valve mechanisms and bleeds to obtain this adjustment so we 35 have obtained this effect by providing supplemental springs, the pressure of which can be applied preferably conjointly to the expression pneumatics so that the rate of movement thereof can be adjusted.

40 The invention is illustrated in the accompanying two sheets of drawings, referring to which

Fig. 1 is a front elevation of the principal part of said mechanism with our improvements applied thereto;

Fig. 2 is a side elevation of the mechanism;

Fig. 3 is a plan through the valve box, taken on the line 3-3 of Fig. 2;

50 Fig. 4 is a detail on an enlarged scale of one of the springs employed;

Fig. 5 is a sectional view on an enlarged scale on the line 5-5 of Fig. 1; and

Fig. 6 is a detail view of the locking mechanism.

It is not believed necessary in this application to describe in detail all the various parts of the valve units as such parts and the operation thereof can be readily understood by reference to our prior application. The 55 expression valve of each unit is operated by an expression pneumatic. The expression controlling pneumatic 49 for the right hand unit has an arm 10 secured thereto connected to which is a link 11 having an eye 12 encircling a rod 13 fitted to slide horizontally in suitable brackets or blocks on the spool box board or bottom. A spring 14 is fitted on carrying pieces or bushings 15-15 fitted on said rod 13. A collar 16 is adjustably secured to the rod 13 near its right hand end. Felt washers 17-17 are arranged between the eye 12 and the left hand bushing 15 and between the right hand bushing 15 and the collar 16 to prevent any clicking of the 60 mechanism. It will be seen that this spring is thus arranged to oppose the collapsing movement of the expression controlling pneumatic 49.

An arm 18 is secured to the left hand expression controlling pneumatic 49. This arm has a piece of felt 19 set in position to engage a roller 20 on the end of a lever 21 pivoted to the left hand valve unit. A link 22 is connected to the lower end of the lever 21 and has an eye 23 fitting on the rod 13. Another spring 14 is arranged on bearing pieces or bushings 15-15 on the rod 13, at the right of the eye 23 of the link 22 and another collar 16 is secured on the rod 13, 65 pieces of felt 17-17 being arranged on said rod 13 between the eye 23 and the left hand bushing 15 and the collar 16 and the right hand bushing 15. It will be seen that this left hand spring 14 is connected to oppose the collapsing movement of the left hand expression pneumatic. It is preferable to apply the action of these springs conjointly to the expression pneumatics and they are arranged in the manner described for this purpose. A handle 24 is secured on the rod 13 and projects up through the key-board of the instrument. This handle has an extending pin or rod 25 which can engage with a piece 26 having notches 27. A spring 28 is 70 secured to the bottom of the handle 24 and

bears on the frame of the instrument so as to hold the lever or handle 24 normally in its forward position, as illustrated in Fig. 5. By pushing in on the handle, the pin 25 will be disengaged from the piece 26 and the rod 13—13 can then be moved horizontally and by releasing the handle the rod can be set in any of its adjusted positions by the re-engagement of the pin with the piece 26. By this arrangement the tension of the springs 14—14 will be applied to oppose the collapsing movement of the expression pneumatics and the application will be made conjointly or evenly and accurately to a similar degree to both expression pneumatics. By this adjustment the action of both expression pneumatics is kept substantially the same, no matter what adjustment is made.

The details and arrangements herein shown and described may be greatly varied by a skilled mechanic without departing from the scope of the invention as expressed in the claims.

Having thus described our invention what we claim and desire to secure by Letters Patent is:—

1. In a musical instrument, a divided action, a mechanism having an expression pneumatic for controlling the tension in one part of the action, a spring, the tension of which can be applied to said pneumatic, another mechanism having an expression pneumatic for controlling the tension in the other part of the action, a spring, the tension of which can be applied to this pneumatic, and means for simultaneously adjusting the action of the springs so that the tensions thereof will be applied with the same differing degrees to the pneumatics.

2. In a musical instrument, the combination of two expression controlling pneumatics, a spring for each pneumatic, and means for simultaneously adjusting the application of the tension of the springs to the pneumatics so that the tensions thereof will be applied with the same differing degrees to the pneumatics.

3. In a musical instrument, the combination of an expression controlling pneumatic, a lever connected thereto, a link extending therefrom and fitting on a rod and arranged

to oppose the collapsing movement of the pneumatic, a spring carried on said rod, a second expression controlling pneumatic, a lever carried by the pneumatic engaging a second lever, a link extending from the second lever and having an eye fitted on said rod, a spring on the rod for this second link and arranged to oppose the collapsing movement of the second pneumatic, and means for adjusting and clamping the rod in different positions, whereby the tension of the springs as applied to the pneumatics can be adjusted to the same degree.

4. In a musical instrument, the combination with a pneumatic, a lever extending therefrom, a slidable rod, a link extending from the lever having an eye fitted on said rod, a spring mounted on said rod in position to be engaged by said eye, a second pneumatic, an arm carried thereby, a pivoted lever which can be engaged by said arm, a link attached to said lever and having an eye surrounding said rod, a second spring mounted on said rod, and means for adjusting and clamping the rod in different positions so that the tensions of the springs can be adjustably applied to the pneumatics to substantially the same degree.

5. In a musical instrument, the combination with a pneumatic, a lever extending therefrom, a slidable rod, a link extending from the lever having an eye fitted on said rod, a spring mounted on said rod in position to be engaged by said eye, a second pneumatic, an arm carried thereby, a pivoted lever which can be engaged by said arm, a link attached to said lever and having an eye surrounding said rod, a second spring mounted on said rod, means for adjusting and clamping the rod in different positions so that the tension of the springs will be adjustably applied to the pneumatics to substantially the same degree, said means consisting of an arm and a notched plate with which a projection on the arm can engage.

In testimony whereof we have hereunto affixed our signatures.

HUBERT J. LA JOIE.
UBERT URQUHART.
